UNITED STATES PATENT OFFICE

156,948

TAMPOON CONTAINER

Suzanne C. Fisher, Flushing, N. Y.

Application April 15, 1948, Serial No. 145,740

Term of patent 3½ years

(Cl. D58—11)

To all whom it may concern:

Be it known that I, Suzanne Chase Fisher, a citizen of the United States residing in the county of Queens and State of New York, have invented a new, original, and ornamental Design for Tampon Containers, of which the following is a specification, reference being had to the accompanying drawing, constituting a part thereof.

Fig. 1 is a perspective view of a tampon container showing my new design, the parts of the container being shown separated,

Fig. 2 is a top plan view thereof, shown in closed position,

Fig. 3 is a side elevational view of Fig. 2, and
Fig. 4 is an end elevational view of Fig. 2.

I claim:

The ornamental design for a tampon container, substantially as shown.

SUZANNE C. FISHER.
